HOISTING ANCHORAGE FOR CAR ROOFS

Filed Jan. 3, 1927

UNITED STATES PATENT OFFICE

EDWIN G. FRANCK, OF DETROIT, MICHIGAN, ASSIGNOR, BY MESNE ASSIGNMENTS, TO HUTCHINS CAR ROOFING COMPANY, OF DETROIT, MICHIGAN, A CORPORATION OF DELAWARE

HOISTING ANCHORAGE FOR CAR ROOFS

Application filed January 3, 1927. Serial No. 158,707,

The invention relates to railway freight cars of that type known as box cars and which are provided with roofs pitched from a central ridge to the eaves.

It is the object of the invention to provide an anchorage for hoisting apparatus used in loading and unloading the cars and one which permits of use at any desired point in the length of the car.

10 It is a further object to avoid any obstruction to the loading capacity of the car which as generally figured must be clear to the interior height of the sides of the body.

With these objects in view the invention 15 consists in the construction as hereinafter set forth.

In the drawings:

Figure 1 is a cross section through a railway box car to which my improvement is 20 applied.

Figure 2 is an enlarged cross section showing the hoist anchorage and

Figure 3 is an enlarged section at right angles to Figure 2.

25 A are the carlines of the roof structure which are formed with pitched portions A' on opposite sides of the car and a central portion A² which is substantially horizontal. Secured to these carlines and extending longitudinally of the car centrally beneath the carlines is a structural member B. This is 30 preferably in the form of a channel member having its web at the top and provided on its opposite sides and at the bottom thereof with outstanding flanges B'.

35 C is a loop or yoke member having the inturned end portions C' which hook over the outstanding flanges B'. This loop is of sufficient strength to carry the load to be hoisted and will transfer the hoisting stresses first to the flanges B' of the member B and then from said member to the carlines. In whatever position the loop is adjusted there will be one or more of the carlines for sustaining the load aided by the reinforcement of all of the other carlines to 40 which the member B is attached.

45 With the construction as described the member B is entirely above the clearance height of the sides of the car and so forms no 50 obstruction to the loading space. The mem-

ber C while projecting downward into the car is shiftable in position so as to avoid obstruction at any one point. The load may be lifted by a rope or cable passing through the loop C and this loop may be shifted to any desired position without the necessity of detaching such rope or cable.

55 What I claim as my invention is:

1. The combination with a car roof comprising a plurality of carlines extending transversely of the car, of a beam extending centrally and longitudinally beneath said carlines and attached thereto, said beam being of inverted channel shape and having its base secured to a plurality of the said carlines, said beam being provided with outstanding flanges at the bottom of its sides and a loop provided with inturned hooks for engaging said flanges adjustable thereon longitudinally of the car.

60 70 75 80 85 90

2. The combination with a car roof comprising a plurality of carlines extending transversely thereof, each carline having pitched side portions and a horizontal central portion, of a U-shaped beam extending centrally longitudinally of the car, said beam having its base secured to the horizontal portions of a plurality of said carlines whereby the beam is entirely above the clearance height of the sides of the car, said beam being provided with outstanding flanges, and a loop having portions slidably engaging said flanges and shiftable thereon longitudinally of the car.

95 100

In testimony whereof I affix my signature.

EDWIN G. FRANCK.
